UNITED STATES PATENT OFFICE.

JOHN SETH, OF BROOKLYN, IOWA.

BOILER.

1,093,733.

Specification of Letters Patent.

Patented Apr. 21, 1914.

Application filed June 28, 1913. Serial No. 776,339.

To all whom it may concern:

Be it known that I, JOHN SETH, a citizen of the United States, residing at Brooklyn, in the county of Poweshiek and State of Iowa, have invented certain new and useful Improvements in Boilers, of which the following is a specification.

This invention is designed as an improvement over my prior Patent #1,059,573, which was granted to me on April 22, 1913, and has for its primary object the association of a stay-bolt with a shell sheet and crown sheet of a boiler so as to allow for the expansion and contraction of the same, without injury to either the stay-bolt or of the sheets.

To those skilled in the art it is obvious that boilers which are at times under a tense heat, expand when in this state and as soon as the heat leaves, and the boiler cools off, the same contracts to a great extent, thereby either causing the boiler sheet to crack or break after a certain length of time or the stay-bolt to break off, which as is well known requires expenditure of much time and labor and very often great inconvenience to repair the same.

It is therefore a very important object of the present invention to provide a stay-bolt which will positively connect the shell sheet and the crown sheet in the usual manner, but will likewise allow for a slight play of the bolt so as to eliminate the danger of either sheets or the stay-bolt breaking.

Other objects as well as the nature, characteristic features and scope of my invention will be more readily understood from the following description taken in connection with the accompanying drawings and pointed out in the claim forming a part of this specification.

Referring to the drawings:—Figure 1 is a sectional view through a portion of an ordinary type of boiler, illustrating the application of my invention; Fig. 2 is a side elevation of an attachment which is in engagement with the stay-bolt and crown sheet; and Fig. 3 is an end view of the same.

In the drawings wherein is illustrated the preferred form of my invention a crown sheet 5 is provided which has arranged in spaced relation thereto in the ordinary manner a shell sheet 6; said sheets being provided with alining apertures 7 and 8, the

aperture or opening 8 which is provided in 55 the shell sheet 6 being threaded for a purpose more fully hereinafter described.

My improved stay-bolt 9 comprises a conical head 10 and enlarged portion 11 which engages with the conical head 10, and a 60 threaded elongated shank 12. The inner face of the conical head 10 engages the inner face of the crown sheet 5, the enlarged portion 11 of the bolt extending through the aperture 7 of said crown sheet and the one 65 end of the threaded shank 12 extending upwardly through the opening 8 of the shell sheet 6. The diameter of the threaded shank 12 is much smaller than that of the opening 8 as shown to advantage in Fig. 1. 70 Threaded on the shank 12 of the bolt 9 is a nut 13, which is of a substantially globular contour, and normally lies in a plane slightly beyond that of the shell sheet 6.

A housing which comprises a bushing or 75 sleeve 14 which is provided with external threads 15 on the one end thereof and external threads 16 on the opposite end thereof, is engaged with the shell sheet 6, the threads 16 thereof being engaged with the 80 threaded opening 8 which is formed in said shell sheet. The external threads 15 which are formed on the outer end thereof are engaged with the threads 17 of the closure or cap 18. The bushing or sleeve 14 preferably tapers toward the threaded end 16 thereof, so as to conform to the configuration of the nut 13 which is engaged on the interior thereof. The cap or closure 18 is preferably of a hemispherical configuration 90 so as to allow for a vertical movement of the bolt 9 without contacting with the inner face of the cap.

A sleeve 19 is carried by the crown sheet 5 and is provided with a plurality of slots 95 or cut out portions 20 which are formed on the end of the sleeve that has engagement with the crown sheet. The sleeve 19 is placed over the bolt 9, and is engaged on the outer end thereof by a nut 21 which 100 holds the sleeve 10 into engagement with the crown sheet 5, said nut being screw threaded on the threaded shank 12 of the bolt 9 so as to prevent the movement of the crown sheet 5 on the stay-bolt.

From the foregoing it is obvious that a certain amount of play is allowed the globular nut 13 in the bushing or sleeve 14, so as

to allow for the expansion and contraction of the boiler without in any way endangering either the sheets or the stay-bolt.

It will be understood that the above description and accompanying drawings comprehend only the general and preferred embodiment of my invention and that various minor changes in detail of construction, proportion and arrangement of the parts may 10 be made within the scope of the appended claim and without sacrificing any of the advantages of my invention.

Having thus fully described my invention, what I claim as new and desire to secure by 15 Letters Patent is:—

In combination with a boiler having a shell sheet and a crown sheet, a stay bolt, having a screw-threaded shank, connecting said sheets, the head thereof being engaged 20 with said crown sheet and the opposite end

extending through a screw threaded opening in said shell sheet, a sleeve having a straight conical inner periphery terminating in a reduced externally screw threaded portion, the latter engaging the threaded opening in said shell sheet, a nut mounted on said shank and in said sleeve, said nut conforming to the configuration of the inner periphery of said sleeve and lying in engagement therewith, whereby stress is 30 passed to said shell sheet from said sleeve when undue pressure is exerted on said nut, and a cap carried by said sleeve.

In testimony whereof I affix my signature in presence of two witnesses.

JOHN SETH.
